Nathaniel Waterman of Boston, Mass.
Letters Patent No 460 Dated May 25th 1852.

The schedule referred to in these Letters Patent and making part of the same

To all Persons to whom these Presents shall come.

Be it known that I Nathaniel Waterman of Boston in the County of Suffolk and State of Massachusetts have invented a new and useful ornamental design for a metallic towel stand; and I do hereby declare that the same is fully described and represented in the following specification and the accompanying drawings, letters figures and references thereof.

Of the said drawings Figure 1 represents a front elevation of my towel stand Figure 2 is an end view of it. Figure 3 is an isometrical perspective view of it.

It consists of two end frames A B of the ornamental design or configuration shewn in the drawings united together by parallel bars C. D. E. ^{end} F. G. The design of the top of each frame is somewhat like that of an arrow head. The bars where they are joined together are connected by ^{balls} a. a. &c.

Ms. 460

I claim the ornamental design or configuration substantially
as represented in the drawings

In testimony whereof I have hereunto set my signature this thir-
teenth day of March AD 1852
